(57) CLAIM

The ornamental design for a toddler's drinking cup with sleeve and top, substantially as shown and described.

DESCRIPTION

FIG. 1 is a perspective view of a toddler drinking cup and top showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken line elements in all views are for illustrative and environmental purposes only and form no part of the claimed design.
